UNITED STATES PATENT OFFICE

LUDWIG B. GLANTZ, OF MINDEN, NEBRASKA

PISTON RING COMPRESSOR

Application filed July 8, 1929. Serial No. 376,629.

The present invention relates generally to tools, and more particularly to a piston ring compressor.

The object of the invention resides in the provision of a tool of this nature which is exceedingly simple in its construction, adjustable to fit different sized pistons and piston rings, easy to manipulate, inexpensive to manufacture, easy to adjust, convenient, thoroughly efficient and reliable in use and operation.

With the above and numerous other objects in view as will appear as the description proceeds, the invention resides in certain novel features of construction and in the combination and arrangement of parts as will be hereinafter more fully described and claimed.

In the drawings:

20 Figure 1 is an end view of the tool embodying the features of my invention.

Figure 2 is a side elevation of the piston showing the tool applied thereto.

25 Figure 3 is a perspective view of the band.

Figure 4 is a perspective view of the keeper fixture.

Figure 5 is a longitudinal section through a portion of the band and the keeper fixture.

30 Figure 6 is a detail sectional view, taken substantially on the line 6—6 of Figure 5, and

Figure 7 is a perspective view of the keeper hooks.

35 Referring to the drawings in detail, it will be seen that numerals 5 and 6 denote two elongated levers pivotally connected intermediate their ends as at 7, and having adjacent extremities terminating in eyes or rings 8, and 9, respectively.

40 The numeral 10 denotes a band which has fixed to one end a rectangular loop fixture 11 with abutting apertured ears 12, extending at right angles from an intermediate portion thereof, with which the eye 9 is engaged. Adjacent the other end, the band is provided with a series of spaced rectangular openings 45 14. Another fixture comprises a plate 15 with a rectangular loop 16 at one end slidable on the band 10 and formed intermediate the ends of the plate 15 is a keeper projection 17,

adapted to project through one of the openings 14 depending upon the adjustment desired and to receive the keeper hook 18 which is substantially U-shaped in formation having one leg longer than the other, the longer leg extending through the keeper projection 17, while the other leg terminates in a right angularly disposed ring or eye member 19 engaged with the eye member 8.

The features of this ring compressor are that a greater variety of sizes may be obtained in one tool. The handles or levers are attached to the fixtures 11 and 15, the latter of which is adjustable so as to accommodate the band to the size of the piston to be operated upon. It will also be seen that the handles may be operated at any desired angle with respect to the band, because of the connections provided at 9 and 12 and 8 and 19. The keeper fixture being once placed in position of the certain-sized piston will always remain that size until the keeper hook is removed from the keeper extension or projection 17 and the projection inserted in another opening or slot 14. The pull at all times will be in the center of the band, thereby causing the wall of the band to always remain parallel when being compressed. This ring compressor can be utilized for the installation of piston rings when the pistons are replaced at the top of the cylinder and can also be used when pistons are replaced from the bottom.

It is thought that the construction, operation, utility and advantages of this invention will now be quite apparent to those skilled in this art without a more detailed description thereof. The present embodiment of the invention has been disclosed in considerable detail merely for the purpose of exemplification, since in actual practice it attains the features of advantage enumerated as desirable in the statement of the invention and the above description. It will be apparent that changes in the details of construction and in the combination and arrangement of parts may be resorted to, without departing from the spirit or scope of the invention as hereinafter claimed or sacrificing any of its advantages.

What is claimed is:

1. In a tool of the class described, an elongated band, a loop fixture at one end of the band through which the other end is slidable, said band being formed adjacent the other end with a series of spaced openings, a keeper fixture comprising a plate having a loop at one end through which the band is slidable and a projection intermediate its ends for insertion through the openings, said projection being open, a keeper hook engageable in the projection and having an eye, said first mentioned fixture having an apertured ear, a pair of levers having ring extremities engageable with the eye and the ear, and means for pivotally connecting the levers intermediate their ends.

2. In a tool of the class described, an elongated band formed adjacent one end with a series of spaced openings, a plate having means engaging the band for slidably retaining the plate on the band, and a projection on the plate for reception in the openings, said projection adapted to be engaged by a tool 25 engaging the opposite end of the band for contracting the latter.

3. In a tool of the class described, an elongated band provided with a series of spaced openings adjacent one end thereof, a plate 30 having means engaging the band for slidably retaining the plate on the latter, said plate having a projection thereon for reception in the openings, said projections being open, a keeper hook engageable with the projection 35 and having means integral with the hook for engagement with a tool engaging the opposite end of the band for contracting the latter.

In testimony whereof I affix my signature.

LUDWIG B. GLANTZ.
